UNITED STATES PATENT OFFICE.

ELMER C. EAGLESON, OF DAYTON, WASHINGTON.

MITER-BOX.

1,259,380.

Specification of Letters Patent. Patented Mar. 12, 1918.

Application filed March 20, 1917. Serial No. 156,119.

To all whom it may concern:

Be it known that I, ELMER C. EAGLESON, a citizen of the United States, residing at Dayton, in the county of Columbia and State 5 of Washington, have invented certain new and useful Improvements in Miter-Boxes, of which the following is a specification.

This invention relates to an improved miter box and has as its primary object to 10 provide a device of this character adjustable for making miter cuts at various horizontal angles.

The invention has as a further object to provide a miter box adjustable for making 15 miter cuts at various vertical angles.

A still further object of the invention is to provide a device of the above described character wherein the miter cuts may be made at various horizontal and vertical angles 20 simultaneously to thus impart a bevel to the miters.

A further object of the invention is to provide an arrangement wherein the posts of the saw guide may be adjusted upon the 25 supporting member therefor for tilting the posts with respect to the vertical and thus inclining the saw for making miter cuts at various vertical angles and to further provide an improved mounting for the said 30 posts.

And the invention has as a still further object to provide an arrangement wherein the posts of the saw guide will be frictionally held at adjustment and wherein means 35 will also be provided for rigidly locking the post at adjustment.

Other and incidental objects will appear as the description proceeds and in the drawings wherein I have illustrated the preferred 40 embodiment of the invention and wherein similar reference characters designate corresponding parts throughout the several views:

Figure 1 is a perspective view of my improved miter box showing the saw guide set 45 for cutting a miter at a vertical and horizontal angle simultaneously, with the swingingly mounted sections of the fence of the box proper displaced to permit the vertical adjustment of the saw,

Fig. 2 is a rear elevation with the saw guide removed and illustrating the mounting of the swingingly supported fence sections of the box proper,

Fig. 3 is a transverse sectional view par-

ticularly showing the mounting of the saw 55 guide,

Fig. 4 is a vertical sectional view illustrating one of the sockets for the posts of the saw guide detached and showing the manner in which the hub coacting with the 60 said socket is fitted therein,

Fig. 5 is a front elevation illustrating the manner in which the post sockets of the saw 65 guide are formed with scales as well as the manner in which the hubs for the said posts are provided with sockets corresponding to the graduations of the said scales and adapted to receive set screws carried by the sockets for rigidly locking the posts at adjustment,

Fig. 6 is an elevation showing one of the 70 sections of the post sockets and particularly illustrating the mounting of the friction band employed for frictionally holding the posts of the saw guide at vertical adjustment,

Fig. 7 is a similar view showing the coacting section of one of the sockets for the saw 75 guide,

Fig. 8 is a fragmentary elevation showing one of the hubs for the saw guide posts, 80

Fig. 9 is a plan view of the bar employed for connecting the posts of the saw guide,

Fig. 10 is a detailed section showing the clamps employed for securing the connecting bar between the posts of the saw guide 85 with the said posts.

Fig. 11 is detail showing the catch.

In carrying out the invention, my improved miter box is formed with a base 10 supported by suitable legs 11. Formed on 90 the forward side of the base substantially midway of the ends thereof, is a segmental plate 12 provided, upon its outer edge, as particularly shown in Fig. 1, with a suitable scale having graduations indicating the degrees of a circle. Upon its inner side, the plate 12 is undercut to provide a flange 13 and formed in the lower edge of the plate is an arcuate series of notches one of which is shown at 14. Opposite the plate 12, the base 100 10 is formed with a bearing 15 and pivotally mounted upon this bearing to extend horizontally beneath the base is an arm 16 of a saw guide, the said arm projecting at opposite sides of the base. This arm, at its rear 105 extremity, is formed with a socket 17 and at its forward extremity, is provided with spaced sockets 18 and 19 respectively. The

purpose of these sockets will presently appear. Fitted through the arm 16 is a post 20 notched to slidably receive the flange 13 of the plate 12 and mounted upon the said arm in front of the post 20, is a catch pin 21. This catch pin is mounted to reciprocate upon the arm 16 and is operable by cams 22 arranged at opposite sides of the said arm and engaged by a yoke 23 pivoted, 10 at its inner extremity, upon the arm immediately in the rear of the pin 21. The arms of the yoke 23 are received by guide pins 24 and interposed between the said yoke arms and the arm 16 to surround the said guide pins are springs 25 normally urging the free extremity of the yoke downwardly and acting upon the cams 22 to yieldably force the catch pin 21 upwardly for engagement within one of the notches 14. Accordingly, by 15 properly manipulating the yoke 23, the arm 16 of the saw guide may be adjusted to various horizontal angles which may be read upon the scale at the front edge of the plate 12. Mounted upon the base 10 to extend 20 longitudinally thereof, is the bed 26 of a box proper and associated with this bed to extend at substantially right angles thereto is the fence 27 of the box. Extending rearwardly from the base in a plane substantially parallel with the bed 26 are brackets 28 and adjustably connected with these brackets by suitable set screws as particularly shown in Fig. 2, are work clamps 29 shiftable transversely of the bed. All of this 25 structure, as thus described, with the exception of the fence 27 may be of any suitable design, it only being necessary for the purposes of the present invention that the arm 16 of the saw guide be pivoted for adjustment in a horizontal plane with respect to the bed 26 of the box proper and provided with sockets similar to the sockets 17, 18 and 30 19 respectively.

The fence 27 of the box proper is, as particularly shown in Fig. 2, provided intermediate its ends with a substantially V-shaped notch 30 and fitting in the said notch are swingingly mounted fence sections 31 confronting, at their inner ends, to define 35 a slot 32 adapted to receive the saw when making ordinary miter cuts at various horizontal angles. Connected with the fence sections 31 are supporting arms 33 therefor which, at their outer extremities, are mounted upon pivot bolts 34 fitted through the fence and provided with suitable wing nuts to clamp against the arms. The fence sections may thus be adjusted to the position shown in Fig. 2 to be held at adjustment by 40 the said bolts or may be swung to the position shown in Fig. 1, projecting beyond opposite ends of the fence with the bolts 34 operable for holding the said fence sections at adjustment. In this latter position of 45 the fence sections, unobstructed movement

of the saw with respect to the vertical within the notch 30 will be permitted. Connected to the fence sections 31, upon the outer side thereof, are retaining fingers 35 arranged to confront the outer face of the fence and mounted upon the inner side of the fence sections 31 are spaced fingers 36 arranged to confront the inner side face of the fence. These fingers are thus adapted to hold the fence sections 31 against lateral displacement within the notch 30. 75

Mounted upon the arm 16 of the saw guide are spaced socket members for the posts of the saw guide. These socket members each include a body 37 provided with spaced upstanding side walls 38 and 39 respectively with the body cut away between the said walls to define an arcuate socket 40. Depending from the body is a cylindrical shank 41 and as will now be observed upon reference to Fig. 4, the socket member is split medially to define coacting mating sections 42 and 43 respectively, the wall 38 being carried by the section 42 while the wall 39 is carried by the section 43. Also, each of the sections carry a portion of the shank 41. Formed in the bottom of the socket 40 upon the section 42 of the socket member is, as shown in detail in Fig. 6, an arcuate shoulder 44 projecting inwardly from the wall 38 of the said section. At one end, this shoulder is formed with a suitable notch while, at the opposite end of the shoulder, the wall 38 is formed with an enlargement providing a beveled seat 45 through which enters an opening 46 from the shoulder 44. Seating upon the said shoulder is an arcuate resilient friction band 47 provided, at one extremity, with a hook 48 engaged within said notch and at its opposite extremity with a threaded shank or terminal 49 extending loosely through the opening 46 and fitted with a nut 50 engaged with the seat 45. As will be clear, the nut 50 may be adjusted upon the shank 49 for shortening the radius of the band. Formed in the upper margin of the wall 38 is an arcuate notch 51 and projecting laterally from the said wall and arranged concentric to the shoulder 44 and band 47 is an arcuate bearing shoulder 52. Projecting laterally from the shoulder 44, at its extremities, are lugs 53. 105

The section 43 of the socket member is, as shown in detail in Fig. 7, formed with an arcuate bearing shoulder 54 projecting laterally from the wall 39 of the said section and of equal radius with the inner face of the friction band 47. Threaded through the said shoulder at one side of the section 43 is a set screw 55 and projecting laterally from the shoulder, at its extremities, are lugs 56. Formed in the upper margin of the wall 38 is an arcuate notch 57 similar to the notch 51 of the section 42 and of equal 110 115 120 125 130

radius therewith. As will now be observed upon reference to Figs. 3 and 4 of the drawings, the sections 42 and 43 of the socket members respectively are arranged to seat 5 flat against each other with the lugs 53 and 56 of the said members abutting for supporting the walls 38 and 39 of the said socket members in spaced relation. The shanks 41 of the said socket members are arranged to 10 removably fit within the sockets 17, 18 and 19 of the arm 16 of the saw guide and for ordinary purposes, one of the said socket members is, as best shown in Fig. 3, fitted within the socket 17 while the other of the 15 said members is fitted within the socket 18. Threaded into the shanks 41 of the said socket members are expander bolts 58 detachably connecting the said socket members with the arm of the saw guide.

20 Arranged to coöperate with the socket members are substantially cylindrical hubs 59 for the posts of the saw guide. The hubs 59 are each formed with a radial saw receiving slot 60 intersecting the axis of the hub 25 and at opposite sides of which are mounted upstanding parallel rods 61 forming one of the posts of the saw guide, these rods being screw threaded into the hub or secured thereto in any other suitable manner. Upon one 30 side, the hub is cut away to provide a substantially circular channel 62 concentric to the axis of the hub and of equal radius with the bearing shoulders 52 respectively of the socket members. Projecting laterally from 35 the hub, at the inner end of the slot 60, is an arcuate bearing shoulder 63 also concentric with the axis of the hub.

The hubs 59 are rotatably received between the walls 38 and 39 of the sockets 40 40 to rest upon the shoulders 54 of the sections 43 of the socket members with the shoulders 52 of the sections 42 of the said members fitting within the channels 62 of the hubs so that the bearing flanges 63 thus seat within 45 in the said shoulders. The hubs 59 may thus be rocked upon the socket members with the friction bands 47 confronting the outer faces of the said hubs. Formed in the outer faces of the hubs 59 are a plurality of sockets 64 corresponding to the graduations of scales 65 upon the sections 43 of the socket members and arranged to coöperate with the 50 said scales are pointers 66 carried by the hubs.

55 As illustrated in Figs. 1 and 3 of the drawings, the posts of the saw guide are supported by the hubs 59 in substantially parallel relation and slidably mounted upon the rods 61 of the said posts are sleeves 67 60 which may be of any suitable character and are adapted to receive a saw, as conventionally illustrated at 68. Connected with the sleeves 67 are spring pressed catches 69 for automatically locking the sleeves to support 65 the saw in elevated position upon the posts of the saw guide. These catches 69 may also be of any conventional design.

Mounted upon the upper extremities of the posts of the saw guide, is a connecting bar 70 therefor, shown in detail in Fig. 9 70 of the drawings. This bar is provided with a plurality of enlargements 71, 72 and 73 respectively, spaced apart to correspond to the spacing of the sockets 17, 18 and 19. Formed in each of the said enlargements are 75 spaced openings 74. The upper ends of the rods 61 of each of the posts of the saw guide are, as shown in detail in Fig. 10, cut away to provide spaced lugs 75 adapted to engage within the openings 74 of the said enlargements respectively and in mounting the bar in position, the said bar is preferably arranged with the enlargement 71 at the front post of the saw guide so that the enlargement 72 will be disposed at the rear post of 80 the said guide. Connecting the bar 70 with the said posts are clamps each including a yoke 76 extending between the rods of one of the saw guide posts and removably fitted through the yoke to extend through the bar 90 are screws 77 threaded into the rods. Mounted upon the yoke is a clamp screw 78 adjustable to engage the bar between the post rods. The clamp screws 78 may, therefore, be operated to tightly bind the bar 70 in 95 engagement with the lugs 75 of the rods of the saw guide posts with the bar thus supporting the rods of each post against movement relative to each other as well as rigidly supporting the posts spaced apart.

100 As will now be seen, the arm 16 may be swung upon the base 10 to adjust the saw for making miter cuts at various horizontal angles. For making a miter cut at a vertical angle, the sections 31 of the fence 105 37 of the box proper are first displaced when the saw is tilted by rocking the hubs 59 of the posts of the saw guide within the socket members therefor to accordingly incline the said posts. Upon consulting either of the 110 scales 65 upon the socket members, the vertical angle of adjustment of the saw guide posts may be easily determined by means of the pointers 66 when, by manipulating the set screws 55 to engage within corresponding ones of the sockets 64, the posts of the saw guide may be rigidly locked at adjustment. However, it may not always be desirable to thus rigidly lock the posts 115 of the saw guide and the friction bands 47 are accordingly provided. By adjusting the nuts 50 of the said bands, these bands may be tensioned against the hubs 59 of the saw guide posts to frictionally engage therewith and accordingly tension the hubs in 120 their rocking movement within the socket members. The frictional action of these bands upon the hubs 59 will, therefore, under ordinary conditions, suffice to hold the posts of the saw guide at adjustment when 130

swung into angular relation with respect to the vertical. Furthermore engagement of the bands 47 with the hubs will eliminate any unnecessary oscillation of the posts or 5 looseness of the said hubs.

It will thus be seen that the posts of the saw guide may be adjusted to tilt the saw for making miter cuts at various vertical angles and in this connection, it is to be 10 observed that the slots 60 in the hubs 59 of the saw guide posts are arranged to register with the notches 51 and 57 of the sockets for the hubs so that the saw may, as illustrated in Fig. 1, be received within the said 15 slots and notches to rest against the bed 26 of the box proper. Furthermore, particular attention is directed to the fact that owing to the mounting of the hubs 59 and the arrangement of the saw between the rods 20 61 of the posts of the saw guide, the saw will always be supported to extend radially of the axes of the hubs and will thus be held to accurately cut a miter at the particular angle of adjustment of the said posts.

25 In view of the preceding description, it will now be understood that the arm 16 of the saw guide may first be adjusted to any desired horizontal angle and the posts of the saw guide then adjusted to any desired 30 angle with respect to the vertical so that the saw may then be operated for making a miter cut at the said horizontal and vertical angles simultaneously to thus impart a bevel to the miter.

35 It will therefore be seen that I provide a particularly effective arrangement for the purpose set forth. For spacing the posts of the saw guide wider apart, the socket member of the forward post of the saw 40 guide may be engaged within the socket 19 of the arm 16 when the enlarged portion 45 73 of the connecting bar 70 will then be disposed to receive the rods of the rear post of the saw guide. This arrangement may sometimes be found necessary in cutting 50 wide timbers and it is to be observed that the rod 70 will, at all times, rigidly support the posts of the saw guide for simultaneous adjustment.

55 Having thus described my invention, what is claimed as new is:

1. A device of the character described including a base, a box proper mounted upon the base and including a fence having a 60 notch formed in the body thereof for receiving a saw, fence sections swingingly mounted upon the body to fit within said notch, the said sections being adjustable to a position supported at the outer ends of the fence to provide a continuation thereof, and a saw guide mounted upon the base and adapted to support a saw to be received within said notch.

65 2. A device of the character described including a base, a box proper mounted there-

on, and a saw guide carried by the base, the said saw guide including an arm, socket members mounted thereon, hubs mounted to rock upon said socket members, posts carried by said hubs, means carried by said 70 posts and adapted to receive a saw, the hubs supporting the posts for adjustment with respect to the vertical upon the arm, and a band carried by one of the said socket members and frictionally coacting with the 75 hub of the said member for holding the post carried by the said hub at adjustment.

3. A device of the character described including a base, a box proper mounted thereon, and a saw guide carried by the base, the 80 said saw guide including an arm, socket members mounted thereon, hubs mounted to rock upon said socket members, posts carried by said 85 hubs, means carried by said posts and adapted to receive a saw, the hubs supporting the posts for adjustment with respect to the vertical upon the arm, a band carried by one of the said socket members and frictionally coacting with the hub of the 90 said member for holding the post carried by the said hub at adjustment, and means adjustable upon the said band for tensioning the band against the said hub.

4. A device of the character described including a base, a box proper mounted thereon, and a saw guide carried by the base, said 95 guide including an arm, posts mounted to rock upon the said arm for adjustment with respect to the vertical thereon, and each formed of spaced rods, a bar connecting the 100 posts, and clamps connecting the said bar with the posts and extending between the rods of the posts respectively for holding the posts rigid with respect to the bar.

5. A device of the character described including a base, a box proper mounted thereon, and a saw guide carried by the base, the 105 said saw guide including an arm, socket members mounted thereon, one of said socket members being formed with a seat having 110 an opening leading therefrom into the said socket member, hubs mounted to rock within the said socket members, posts carried by the said hubs, the said posts being adapted to receive a saw and being adjustably supported by the said hubs for positioning the saw with respect to the vertical, means extending within the said socket member and secured at one extremity thereof with the opposite extremity of the said means freely 115 fitted through the said opening, and means adjustable upon the said first-mentioned means to coact with the said seat for tensioning the said first-mentioned means to engage the hub carried by the said socket 120 member for holding the post mounted upon the said hub at adjustment.

6. A device of the character described including a base, a box proper mounted thereon, and a saw guide carried by the base, 130

5 said saw guide including an arm, posts mounted to rock upon the said arm for adjustment with respect to the vertical thereon and each formed of spaced rods, a bar connecting the posts and fitted over the upper ends of said rods, and clamps extending between the rods of the said posts respectively and connecting the bar thereto, the said clamps each including means adjust-
10 able to engage the bar at a point between the rods of one of said posts.

7. A device of the character described including a base, a box proper mounted thereon, and a saw guide carried by the base, the
15 said saw guide including an arm, socket members mounted upon the arm and provided with shanks fitted through the said arms for connecting the said socket members thereto, the said socket members being each
20 split medially to provide mating sections coacting to define a socket, means adjustable between the sectional portions of the shanks of said socket members for expanding the said shanks to engage the said arm, hubs mounted to rock within said sockets, and posts carried by said hubs and adapted to support a saw.

8. A device of the character described including a base, a box proper mounted thereon, and a saw guide carried by the base, the
30 said saw guide including an arm, socket members mounted upon the said arm, hubs mounted to rock within said socket members and formed with radial slots intersecting
35 the axes of the said hubs, and posts carried by the hubs and adapted to support a saw to be received within the said slots.

9. A device of the character described including a base, a box proper mounted there-
40 on and including a fence having a notch

formed in the body thereof for receiving a saw, fence sections mounted in said notch, and arms pivotally connected to the body of the fence and engaged with the said fence sections, the said arms supporting the said
45 sections for swinging movement to a position supported by the arms at the outer ends of the fence body to form a continuation of the fence.

10. A miter box including a base, and a
saw guide carried thereby, the said saw
guide including a socket member, a hub
mounted to rock upon the socket member,
saw carrying means mounted upon the hub,
and means mounted upon the socket member
55 to frictionally engage about the hub for
holding the hub at adjustment in its rocking
movement.

11. A miter box including a base, and a
saw guide carried thereby, the said saw
guide including a socket member, a hub
mounted to rock upon the socket member,
saw carrying means mounted upon the hub,
means upon the socket member to friction-
ally engage about the hub for holding the
65 hub at adjustment in its rocking movement,
and means for tensioning the said last-men-
tioned means.

12. A miter box including a base, and a
saw guide carried by the base, the said saw
guide including a socket member, a hub
mounted to rock within the socket member,
saw carrying means mounted upon the said
hub, a flexible strip mounted in the socket
member to frictionally engage the hub for
75 holding the said hub at adjustment in its
rocking movement, and means to tension the
said strip.

In testimony whereof I affix my signature.
ELMER C. EAGLESON. [L. S.]
